(57) **CLAIM**

The ornamental design for an automobile tire, as shown and described.

DESCRIPTION

FIG. 1 is a front view of the automobile tire of the invention; FIG. 2 is a rear view thereof;

FIG. 3 is a left-side view thereof;

FIG. 4 is a right-side view thereof;

FIG. 5 is a partially enlarged right-side view thereof; and, FIG. 6 is an enlarged end elevational view of the section VI in FIG. 5, taken along the line 6—6 in FIG. 5.

The broken line showing of a tire inner bead and tread surface is for illustrative purposes only and forms no part of the claimed design. The broken lines on the inner and outer edges of the sidewall represent the boundaries of the claimed design, and form no part thereof.
